J. F. STURROCK.
MACHINE FOR PRINTING OIL CLOTH AND THE LIKE.
APPLICATION FILED FEB. 26, 1916.

1,216,181.

Patented Feb. 13, 1917.

By his Attorney.

Rev. Dr. Cooper of Agard.

UNITED STATES PATENT OFFICE.

JAMES FLEMING STURROCK, OF NEWARK, NEW JERSEY, ASSIGNOR TO THE NAIRN LINOLEUM COMPANY, OF KEARNEY, NEW JERSEY, A CORPORATION OF NEW JERSEY.

MACHINE FOR PRINTING OIL-CLOTH AND THE LIKE.

1,216,181.

Specification of Letters Patent. Patented Feb. 13, 1917.

Application filed February 26, 1916. Serial No. 80,608.

To all whom it may concern:

Be it known that I, JAMES FLEMING STURROCK, a subject of the King of Great Britain, residing at Newark, county of Essex, and 5 State of New Jersey, have invented certain new and useful Improvements in Machines for Printing Oil-Cloth and the like, of which the following is a full, clear, and exact description.

10 This invention relates to machines for printing linoleum, oilcloth, and the like. In machines for that purpose the fabric to be printed is passed in the form of a long strip step-by-step under a number of vertically 15 movable printing blocks which are raised periodically in order to have the colors applied to them and are then lowered to make the impression. The printing blocks are usually operated simultaneously, but in 20 some kinds of work it is desirable to have one or more blocks operate only once while the rest are operating two or more times. The present invention relates to this feature, and its object is to provide simple and effective 25 mechanism by which any block with which it is used can be held idle during practically any number of cycles. To this and other ends the invention consists in the novel features of construction and combinations 30 of elements hereinafter described.

While the invention can be applied to various machines for the purpose, the embodiment illustrated in the accompanying drawings is designed particularly for use with 35 the machine described in Eisenhardt Patent No. 476,135, dated May 31, 1892. Referring now to the drawing,

Figure 1 is a side view of a portion of the machine, showing one of the printing blocks 40 and the mechanism for operating it.

Fig. 2 is a side view, on a larger scale, of the preferred form of my invention.

Fig. 3 is a detail view of one of the operating cams and the gear for operating the 45 same.

Fig. 4 is a side view of the lever which constitutes one of the cam followers used in the throw out mechanism.

The printing block 10 (the underside of 50 which is the printing surface) is above the table or platen over which the oilcloth or other fabric is fed, and is supported at its ends by a pair of side members or standards (one of which is shown at 11) sliding vertically in suitable guides 12 suitably mounted

on the side frames 13 of the machine. It is to be understood that the complete machine comprises a number of printing blocks, each with its own actuating mechanism, the latter being driven by a longitudinal power-shaft 60 14. While the block is in its upper position and the fabric to be printed is at rest, the color is applied to the printing surface of the block by the usual means, not shown.

The block is raised and lowered through 65 the agency of cams 15 at each side of the machine, fixed on a transverse shaft 16 which is driven from the longitudinal shaft 14 in any convenient manner, as by means of bevel gears, not shown. The cams mentioned coöperate with anti-friction rollers 17 on plates 18 adjustably connected to the side-members 11 by means of screws 19. On the plates are fingers 20, which may be engaged by latches 21 on depending levers or 70 arms 22 when the block is in its upper position so as to hold the block in that position, out of operation. The lever referred to is normally held out of engagement with the finger by a spring 23. When it is desired to 75 hold the block out of operation the arm 22 is swung against the tension of its spring just as the block and slide are momentarily raised to their highest point (the position shown in Fig. 1 of the drawing) by a dwell 80 85 on the cam 15. The latch is thus swung under the finger. Then as the block starts to descend the latch engages the finger and so supports the block and prevents further descent. 90

According to my invention the operation of the lever or arm 22 to control the operation of the printing block is effected automatically, the preferred mechanism for the purpose being shown in Fig. 2 of the drawing, in which the same reference numerals are used to designate the parts shown in Fig. 1. The end of shaft 16, or a suitable extension thereof, is provided with a pinion 24, meshing with a gear 25 journaled 100 in an L-shaped hanger 26 depending from the stationary side bar 27. This gear is rigidly connected to, and drives, a cam 28, co-operating with an anti-friction roller 29 on a lever 30, which is fulcrumed on the horizontal arm of the hanger 26 and is adjustably connected to the latching arm 22 by means of a link 31. It will therefore be seen that when the rise on the cam engages the lever 30, the latching arm 22 is swung 105 110

leftwardly, bringing the detent 21 into the path of the finger 20, thereby holding the printing block 10 (Fig. 1) in its upper or inoperative position, as shown. When the 5 drop on the cam reaches the roller 29, after the cam 15 has lifted the block slightly so that the finger 20 is clear of the detent 21, the spring 28, retracts the arm 22, thereby leaving the printing block free to descend.

10 The design of the machine is usually such that the printing block can rise and descend once in each rotation of the cam 15. In my improvement, which is intended to hold the block raised during one or more revolutions 15 of the cam (during which period other blocks, not shown, may be in operation) the time during which the block is inoperative depends upon the configuration of the cam 28, or its speed of rotation relative to the 20 speed of cam 15, or upon both these factors. The first involves changing the cam, and hence requires a number of different but interchangeable cams. I therefore prefer to use the same cam, and then vary its speed as 25 required, changing the gears to obtain the desired sequence of operations. In this case I have provided multiple centers 32 for the stud carrying the gear 25 and cam 28, and similar centers 33 for the fulcrum stud of 30 lever 30. Then merely by changing gears and shifting the fulcrum of the lever the desired operation can be obtained.

35 The effective length of the link 31 is regulated by means of the nut 34, threaded on the end of the link which passes through the yoke 35 pivoted in the top of lever 30. The link can slide in the yoke but is normally held with the nut bearing against the yoke by a rather stiff spring 36, thus afford- 40 ing a yielding connection so that if the latch 21 be swung into the path of the finger 20 while the printing block is down the finger can, when the block rises, cam the latch out of the way. Then tension of 45 spring 36 is regulated by the nut 37.

It will be understood that both sides of the machine are equipped alike, and that similar mechanism is provided for each block so that each can be controlled independently of all the rest.

50 The cam 28 and the gear that drives the same are coaxial with each other and are detachably connected together in any convenient manner to permit substitution of one gear for another as described. For this purpose the cam and each gear used there- 55 with can be provided with registering apertures 38, on opposite sides of their axes, as shown in Fig. 3, to receive removable connecting pins or screws, not shown. The lever 30 is preferably composed of two flat strips 30^a, Fig. 4, fixed on a hub 30^b, with the roller 29 and yoke 35 mounted between the strips.

60 It is to be understood that the invention 65

is not limited to the specific mechanism herein described but can be embodied in other forms without departure from its spirit.

What I claim as new and desire to secure 70 by Letters Patent is:

1. In a printing machine for the purpose described, the combination of a printing block, means for raising and lowering the same periodically, means to hold the printing block in raised position, mechanism for operating the last-named means, and means including a variable speed driving means for enabling said mechanism to be operated once in a plurality of periods as desired. 80

2. In a printing machine for the purpose described, the combination of a printing block; means, including a cam, to raise and lower the printing block periodically; means to hold the printing block in raised or inoperative position; and mechanism, including a cam, for operating the last named means and permitting the speed of the second-named cam to be varied relatively to the speed of the first, whereby the printing 90 block may be held in raised or inoperative position during such number of periods or cycles as may be desired.

3. In a printing machine for the purpose described, the combination of a printing 95 block; means to raise and lower the same periodically; means, including a cam, to hold the printing block in raised or inoperative position; and driving mechanism for the cam, enabling the speed thereof to be 100 varied whereby the printing block can be held in raised or inoperative position during such number of periods or cycles as may be desired.

4. In a printing machine for the purpose 105 described, the combination of a printing block; means to raise and lower the same; means to hold the printing block in raised or inoperative position; mechanism, including a cam, to actuate the last named means 110 intermittently; gearing connecting the cam with the block raising and lowering means to drive the cam in harmony with the latter; and means permitting change of gearing to vary the speed of the cam.

5. In a printing machine of the kind de- 115 scribed, the combination of a printing block; means, including an actuating shaft, to raise and lower the printing block; a movable detent to hold the printing block in raised 120 position; a cam to actuate the detent; gearing connecting the cam with said shaft to drive the cam in harmony with the block raising and lowering means; and bearings for the gearing, permitting change of gear- 125 ratio to vary the speed of the cam.

6. In a printing machine for the purpose described, the combination of a printing block; means, including an actuating shaft, to raise and lower the printing block; means 130

to hold the printing block in raised position; a cam to actuate the last named means; gearing connecting the cam with the shaft to drive the cam in harmony with the block 5 raising and lowering means; and multiple bearings for the gearing, permitting substitution of gears to vary the speed of the cam relative to the speed of said shaft.

7. In a printing machine for the purpose 10 described, the combination of a printing block; means, including an actuating shaft, to raise and lower the printing block; means, including a link and a lever to actuate the same, for holding the printing block in 15 raised position; a cam coöperating with the

lever to rock the same and reciprocate the link periodically; a pinion on the aforesaid shaft; a gear detachably and co-axially connected with the cam and meshing with the said pinion to drive the cam in harmony 20 with the block raising and lowering means; multiple bearings for the gear and cam, permitting substitution of gears to vary the speed of the cam relative to the speed of the said shaft; and multiple bearings for the 25 fulcrum of said lever to permit change in the position thereof in correspondence with change in the position of the cam.

In testimony whereof I affix my signature.
JAMES FLEMING STURROCK.
